Primary Examiner — Leanne Was-Englehart

(57) **CLAIM**

The ornamental design for a front automobile grille, as shown and described.

DESCRIPTION

FIG. 1 is a front elevation view of a front automobile grille showing our new design;

FIG. 2 is a front and left-side perspective view thereof; FIG. 3 is a front left-side perspective view showing where the closeup for FIG. 4 is located;

FIG. 4 is a close-up of the front and left-side perspective view thereof;

FIG. 5 is a front and right-side perspective view thereof;

FIG. 6 shows where the closeup for FIG. 7 is located;

FIG. 7 is a close-up of the front and right-side perspective view thereof;

FIG. 8 shows where the closeup for FIG. 9 is located;

FIG. 9 is a close-up of a bottom and front left-side perspective view thereof;

FIG. 10 shows where the closeup for FIG. 11 is located; and, FIG. 11 is a closeup of a bottom and front right-side perspective view thereof.

The evenly spaced broken lines depict portions of the front automobile grille that form no part of the claimed design. The dot-dashed broken lines depict the limits of the enlarged view and form no part of the claimed design.

1 Claim, 11 Drawing Sheets
